(57) **CLAIM**

The ornamental design for a cookware vessel, as shown and described.

DESCRIPTION

FIG. 1 is a perspective view from above the “cookware vessel”, showing my new design;

FIG. 2 is a top plan view thereof;

FIG. 3 is a bottom plan view;

FIG. 4 is an elevation view thereof; and,

FIG. 5 is a perspective view thereof from the bottom.

The characteristic feature in the design resides in providing a contrasting band of color to the middle external sidewall portion of the cookware vessel, whereas the surrounding upper portion, from the rim downward, and lower portion, from the bottom upward, of the same cookware vessel have a bright metallic finish.

Broken lines are intended to show associated environmental matter for illustrative purposes only, not being part of the claimed design.
